(57) **CLAIM**

The ornamental design for a PTZ camera, as shown and described.

DESCRIPTION

1. PTZ camera

1.1 is a front and right side perspective view of a PTZ camera showing my new design;

1.2 is a rear, right and bottom perspective view thereof;

1.3 is a front elevation view thereof;

1.4 is a rear elevation view thereof;

1.5 is a left side elevation view thereof;

1.6 is a right side elevation view thereof;

1.7 is a top plan view thereof; and

1.8 is a bottom plan view thereof.

The broken lines depict portions of the PTZ camera that form no part of the claimed design.

The unshaded surfaces shown between the solid lines and the broken lines form no part of the claimed design.
